UNITED STATES PATENT OFFICE.

ALBERT P. HOWES, OF WORCESTER, MASSACHUSETTS.

AUTOMATIC FLOAT TANK-COCK.

SPECIFICATION forming part of Letters Patent No. 402,596, dated May 7, 1889.

Application filed July 5, 1888. Serial No. 279,007. (No model.)

To all whom it may concern:

Be it known that I, ALBERT P. HOWES, a citizen of the United States, residing at Worcester, in the county of Worcester and State of Massachusetts, have invented certain new and useful Improvements in Automatic Float Tank-Cocks, of which the following, together with the accompanying drawings, is a specification sufficiently full, clear, and exact to enable persons skilled in the art to which this invention appertains to make and use the same.

The object of my present invention is to provide an automatic float-valve that will be efficient and quiet in its action, which can be manufactured with economy and practical facility, and in which the valve-puppet is sufficiently loose and free to be self-adjusting to its seat, while it is protected from being forced out of position by the flow of water through the cock; also, to connect the valve-puppet and float-lever head in a manner that will insure the action of the valve without liability of cramping or binding at the connecting-joint. These objects I attain by mechanism constructed as illustrated and described.

In the drawings, Figure 1 is a vertical sectional view illustrating my invention. Fig. 2 is a horizontal section at line *w w* on Fig. 1. Fig. 3 is a top plan view of the float-lever head; and Fig. 4 is a vertical section at line *x x*, Fig. 1, showing the valve opened.

In referring to parts, *A* denotes the shell or body, which is formed with an internal chamber, *a*, of suitable dimension to receive the valve mechanism, and with an attaching-nipple, *A'*, through which the inlet-passage leads to the chamber *a*, and with a delivering-tube, *A''*, through which the liquid is discharged when the valve is opened. A raised annular valve-seat, *e*, is formed within the chamber *a* about the exit-passage, and a second seat, *f*, or flat annular surface is formed around said valve-seat *e*.

The valve-puppet *B* is made in the form shown, and is disposed within the cock to close onto the seat *e* in the direction of the discharge-pressure. Said puppet is provided with an upward extension that carries an annular flange or disk, *b*, and with a dependent stem, *B'*, that extends down through the exit-

passage to a position somewhat below the end of the delivery-tube *A''*. Arranged within the chamber *a*, and inclosing the puppet *B*, is a cylinder or thimble, *C*, the lower open end of which rests upon and forms a close joint with the annular seating-surface *f* around the valve-seat *e*, while its upper end is closed, so as to form a chamber, *c'*, above the puppet and disk *b*. Small holes *i* are formed through the cylinder *C* below the position of the disk *b*. The cylinder *C* fits comparatively close, but not tightly, about the disk *b*, so that the valve-puppet will be confined in proper relation to its seat *e*, while free to adjust itself thereon as the valve closes.

The top of the body-shell is closed by a screw-cap, *A''*, the flanges *d* of which loosely confine the top of the cylinder, while a space, *D*, of about one-eighth inch (more or less) is left between the cap and cylinder, to permit of said cylinder *C* being lifted from its seat *f* by the puppet-head at the latter portion of its upward range of movement. A lug, *l*, is provided to prevent displacement of the cylinder by the force of the liquid flowing into the chamber *A* at the inlet-passage. The lower end of the valve-stem *B'* is furnished with a rounded point at *I* and with an annular flange, *J*, as illustrated.

H denotes the lever for operating the valve-puppet under control of the ball or float *F*. Said lever is fulcrumed at *h* to an arm or arms, *G*, projecting from the shell or body *A*, and is preferably formed or provided with a hub or socket, *H'*, into which the arm *F'*, that carries the ball, is fixed or screwed. The head of the lever is formed with a step or surface, *I'*, upon which the point *I* of the valve-stem engages, and with lugs or projections *m m*, that overhang the flange *J*, as illustrated; also with a shoulder at *n*, which prevents the flange *J* from escaping from beneath the overhanging ends *m m*. Sufficient space is provided between the flange *J* and ends *m* to allow great freedom of action and to permit of the valve automatically lifting from its seat *e* to relieve any vacuum or back-pressure or to admit air to the pipes when the water-supply is shut off.

The peculiar form of the lever-head, with its hooks *m*, is such that it can be hooked onto

the valve-stem flange J before the lever is placed in position and the fulcrum-stud h introduced; but when the parts are put together and the stud h fitted in the lever and stem 5 are loosely but securely interlocked with each other.

In Fig. 1, T indicates a portion of the tank, and W the water-level in said tank.

In the operation, when the water in the tank 10 is drawn down, the float F falls and the head of the lever H is raised, and the surface I', pressing against the point I of the stem B', forces up the valve-puppet B from its seat e and allows the liquid to escape through the exit- 15 passage. Assuming that the fall of the float is sufficient, the cylinder C is also lifted from its seat f, (see Fig. 4,) allowing the liquid to pass beneath its lower end to the discharge. Then as the float F rises with the water-level 20 the valve-puppet B and cylinder C descend gradually, the cylinder reaching its seat f before the valve B reaches its seat, thereby cutting off the flow of water, except such as passes through the holes i, and reducing the 25 pressure on the puppet D to an extent that will give easy and quiet closing action to the valve. If the valve for any reason fails to close upon its seat, the lifting of the ball or 30 float F above its normal level will cause the projections m to press downward upon the top of the flange J, and thus force the puppet to close the passage.

The valve-puppet B, having the disk b and the cylinder C arranged within the cock, as 35 illustrated, can be employed with an operating float-lever that is connected to the valve-stem otherwise than herein shown, equivalent action of the valve being effected. I prefer,

however, to connect the lever and stem as herein illustrated.

In my previous application, Serial No. 254,353, I have described a faucet wherein a puppet-valve surrounded by an inverted cup is employed. It will therefore be understood that I do not in my present application 45 broadly claim such feature of construction.

What I claim as of my invention, and desire to secure by Letters Patent, is—

1. The combination, substantially as described, of the shell A, provided with the arm 50 (or arms) G and valve-seat e, the valve B, arranged to close onto said seat and having its depending stem provided with the flange J and rounded point I, the operating-lever H, provided with the step surface I', overhanging 55 ends m, and shoulder n, and the fulcrum-pin h, connecting said lever to the arm G, for the purposes set forth.

2. In combination, substantially as described, the body-shell A, having the internal 60 chamber, a, with inlet and outlet passages, valve-seats e and f, and screw-cap A³, the puppet-valve B, having the disk b and dependent stem B', provided with flange J and point I, the lifting-lever H, fulcrumed at h to the 65 body-arm G, and engaging the point and flange of said valve-spindle, and the buoyant float F, all constructed and arranged for operating as and for the purpose set forth.

Witness my hand this 2d day of July, A. 70 D. 1888.

ALBERT P. HOWES.
